CLAIM

The ornamental design for a heated towel rail, as shown and described.

DESCRIPTION

FIG. 1 is a front and right side perspective view of a heated towel rail showing our new design;

FIG. 2 is a front elevational view thereof;

FIG. 3 is a right side elevational thereof;

FIG. 4 is a left side elevational view thereof; and,

FIG. 5 is a top plan view thereof.

Where included, broken lines are for illustrative purposes only and form no part of the claimed design.
